SHOE SOLE LEVELING, SHAPING, AND
SECURING UNIT

George Laganas, Lowell, Mass.

Application January 18, 1933, Serial No. 652,390

2 Claims. (Cl. 12—33)

This invention relates to a shoe sole leveling, shaping and securing unit, and has for its object to provide, in a manner as hereinafter set forth, a unit of the class referred to, operated from a continuous supply of compressed air for expeditiously and simultaneously leveling, shaping and securing a shoe sole having a cementitious coating, to an upper position on a working last by the application to the sole for a substantial period of a continuous building up pressure derived from an open compressed air supply, thereby resulting in the sole being formed with a permanent bend and curve to conform to that of the last and for securing of the upper and sole in fixed relation with respect to each other.

A further object of the invention is to provide, in a manner as hereinafter set forth, a unit of the class referred to whereby the sole is simultaneously leveled and shaped in unison with the securing of it to a shoe upper mounted on its original working last, under such conditions providing for increased production and a material decrease in the cost of labor.

25 A further object of the invention is to provide, in a manner as hereinafter set forth, a sole leveling, shaping and securing unit capable of being used in connection with the manufacture of all types of shoes.

30 A further object of the invention is to provide, in a manner as hereinafter set forth, a unit for the purpose referred to whereby it does not necessitate in its use, to accomplish a sole leveling, shaping and securing operation, the employing of separate iron beating out forms or lasts, as is the case at present, more especially the employment of different shapes of forms or lasts for different styles and sizes of shoes.

35 Further objects of the invention are to provide, in a manner as hereinafter set forth, a sole leveling, shaping and securing unit which is comparatively simple in its construction, strong, durable, compact, thoroughly efficient in its use, readily assembled and comparatively inexpensive to manufacture.

40 To the above ends essentially, and to others which may hereinafter be set forth, the invention consists of such parts, and such combination of parts which fall within the scope of the invention as claimed.

45 The unit includes a presser element and a clamping element coacting to provide a simultaneous leveling, shaping and securing action on the sole. The unit is shown, by way of example as supported upon a revolvable carrier hav-

ing a compressed air conducting means leading to the presser element, means for opening the presser element to the atmosphere, and means for releasing the clamping element. It is to be understood that the unit can be mounted upon any suitable support therefor and that means other than that as shown and hereinafter referred to may be employed to open the presser element to the atmosphere and to release the clamping element. It is to be further understood that the presser element can be opened to the atmosphere manually and the clamping element released manually if desired after the activity of the unit for a desired period.

In the drawings:

Figure 1 is a side elevation of the unit mounted on a supporting means, the latter being shown in section.

Figure 2 is a top plan view of the compressed air operated presser element of the unit.

Figure 3 is a sectional detail illustrating the controlling valve for the presser element.

Figure 4 is a side elevation of the unit mounted upon a supporting means and with the latter and presser element in section.

Figure 5 is a sectional elevation of the clamping element looking towards the front of the latter and with the element mounted on a support.

Figure 6 is a fragmentary view in front elevation of a revolvable carrier having the unit mounted thereon.

Figure 7 is a fragmentary view in cross section of the clamping element illustrating the shoe upper clamping or abutment member.

Figure 8 is a fragmentary view in cross section of the clamping element showing the last clamping or abutment member.

Figure 9 is a perspective view of the locking lever of the clamping element and further showing in perspective a shifting means for the lever.

Figure 10 is a detail in side elevation illustrating the shoe upper clamp or abutment.

Figure 11 is a side elevation of the shoe upper clamp or abutment disassembled.

Figure 12 is a perspective view of the latching member for the sections of the shoe upper clamp or abutment.

Figure 13 is a front elevation of a support forming a part.

The unit forming the subject of this application is of the same construction as that disclosed in my application Serial Number 635,708, filed September 30, 1932.

The unit includes a compressed air operated presser element and a clamping element indi-

70

105

110

cated generally at 1, 2 respectively. The elements coact to provide a leveling, shaping and securing action on the sole with respect to an upper 3 carried by a working last 4. The sole 5 after being acted upon is fixedly secured to the upper 2. The sole after the leveling, shaping and securing action will be formed with a permanent bend and curve conforming to that of the last.

- 10 The element 1 comprises a cup-shaped body portion 5 of substantially oval contour in plan of the desired depth and having a low part 6, an upwardly extending curved intermediate part 7 and an inwardly inclined high part 8. Integral 15 with and flush with edge of body portion 5 is an outwardly extending flat endless flange 9 of greater width than the width of said top edge. The outer end of the bottom of high part 8 is formed with an opening 10 for a purpose to be referred to.

Seated on the flange 9 may be one or a plurality of superposed washers of like form, but one being shown and indicated at 11. The washer is coextensive with flange 9. Mounted on the 25 washer 11 is a presser member 12 formed of a plurality of superposed plies of resilient material. The member 12 conforms in contour to that of the body portion 5 in plan and has its edge flush with the outer edge of washer 11. Mounted on the 30 marginal portion of the outer face of member 12 may be one or more washers, but one being shown and indicated at 13. The washer 13 conforms in contour to that of washer 11 and is flush with the outer edge of member 12. Seated upon washer 13 and of the same width as that of the latter is a metallic band 14 conforming in contour to that of flange 9. The upper face of band 14 is formed with parallel spaced endless ribs 15. The inner edges of washers 11, 13 and band 14 are flush with the inner faces of the sides and ends of body portion 5. The body portion 5 in connection with washer 11 and member 12 provides a compressed air receiving chamber 16. The flange 9, washers 11, 13, member 12 and band 14 are secured together by spaced holdfast devices 17. The member 12 forms the top wall of chamber 16 and is adapted to have the work to be acted upon seated thereon, the work being the sole having in superimposed relation thereto the working last 45 carrying the shoe upper. The member 12 is of greater width and length than that of the work and is formed with a lower part 18, an intermediate upwardly extending curved part 19 and a high part 20.

The opening 10 is adapted to have secured therein a compressed air supply and exhaust controlling means referred to generally at 21. The said means includes a pipe section 22 which has one end secured to the wall of opening 10 and permanently communicates with chamber 16, a valve housing 23 having ports 24, 25 and 26, nipples 27, 28 and 29 into which respectively open the ports 24, 25 and 26, a rotatable valve 30 arranged in housing 23 and formed with a diametrically extending channel 31 common to ports 24, 25 and 26, a channel 32 extending from channel 31 and associated with port 24, a valve stem 33 extended at one end from one end of housing 23, a handle 34 carried by the extended end of stem 33 for shifting the valve 30 clockwise and anti-clockwise, and a pipe section 35. The pipe section 22 extends into and is secured to nipple 27. The pipe section 35 extends into and is secured to nipple 28 and is adapted to have a source of compressed air coupled thereto. Preferably

pipe section 35 will be in the form of an L having its smaller leg attached to nipple 28.

When channel 31 registers with ports 24, 25 the chamber 16 is to open to a continuous supply of compressed air whereby a continuous pressure will be built up in said chamber against member 12 for the purpose of applying a leveling, shaping and securing action of the sole. When channel 32 registers with port 24, ports 24, 25 are closed to each other and port 26 registers with one end of channel 31 whereby the compressed air supply is cut off and chamber 16 exhausts to the atmosphere. The port 26 and nipple 29 provide an exhaust for housing 23. The port 24 provides a combined intake and exhaust port for chamber 16. The port 25 constitutes an air intake for housing 23.

The element 1 may be anchored stationary to a support therefor by any suitable means, and by way of example there is shown a pair of oppositely disposed angle-shaped lugs 35', 36 depending from the low and high parts 6, 8 respectively of body portion 5. The lug 35' is adapted to interengage with the support and the lug 36 fixed to the support by a holdfast means. It is to be understood that the lugs may be dispensed with and that any suitable means to maintain element 1 stationary may be employed.

The clamping element 2 comprises a pivoted spring controlled hanger 37 in the form of a bar 105 of the desired length and formed with an enlarged outer end 38 formed with a transverse opening 39. The hanger 37 has depending therefrom at its outer end a lug 40 and rearwardly and in proximity to its vertical median a depending lug 41. Extending through the opening 39 and disposed in a plane at right angles to the plane of the hanger 37, is a cross head 42, having reduced outer ends 43, upon which are pivotally mounted the upper ends of a pair of parallel 115 spaced latching members 44 of like form. The upper ends of members 44 are retained on the outer ends 43 of the cross head 42 by cotter pins 45. Each latching member is in the form of an angle-shaped link formed of an upper and a lower oppositely inclined downwardly directed legs 46, 47 having a curved portion 48 interposed therebetween. The leg 46 is of a greater length and its inclination is less than that of leg 47. The body portion 5 of the presser element is 125 positioned between the members 44 and above the legs 47. The members function to hold down and to elevate the outer end of hanger 37.

The cross head 42 at the vertical center thereof is provided with an opening 49 having the wall 130 thereof threaded and engaging with said wall is an adjusting device 50 for vertically moving the cross head relative to the top and bottom walls of opening 39, the latter being of greater height than the cross head. The device 50 extends 135 through an opening 51 in hanger 37 and carries a set nut 52 for arresting vertical movement of the cross head.

Overlapping the hanger 37 approximately centrally thereof is a holder 53, of inverted U-shape, 140 having the sides 54 thereof formed with rearwardly disposed offset extensions 55 provided with lateral lugs 56. The top 57 of holder 53 has a vertical opening 58, through which extends an adjusting device 59 having threaded engagement 145 with the wall of a vertical opening 60 formed in hanger 37 whereby the latter is adjustably connected to the holder 53. The device 59 carries a lock nut 61. The rear end of hanger 37 has anchored thereto the upper ends of a pair of con- 150

trolling springs 62. The lower ends of the latter are to be anchored to the support for element 1 and one example of anchoring the lower ends of said springs will be hereinafter set forth. The 5 device 59 functions to adjust hanger 37 relative to holder 53 and for controlling the upward movement and angular disposition of hanger 37 with respect to a pair of uprights to be referred to.

The holder 53 is pivotally mounted through 10 the medium of the lugs 56 being mounted in a pair of oppositely disposed spaced uprights or 15 arms 63. Each of the latter has an inset upper portion 64 terminating in an enlarged centrally apertured upper portion 65. The lower end of 20 each upright is anchored stationary and by way of example the lower end of each upright is of annular form and consisting of a pair of semi-circular sections 66. When the uprights have 25 annular lower ends, such ends are adapted to encompass a bar 67 or other support and be fixedly secured to the latter by holdfast means 68 which couple the sections of the lower end of each upright together. It is to be understood that the uprights may be formed in any suitable manner 30 for the purpose of anchoring them stationary to a support, and that the means as shown is illustrated by way of example.

Rotatably mounted in the hangers 40, 41 is 35 an adjusting member 70 for a pair of clamping members or abutments 71, 72 to be referred to. The member 70 is in the form of a round bar provided with a pair of spaced groups 73, 74 of threads, one group being left and the other right hand threads, which engage with said 40 clamping members or abutments for shifting them relatively towards and from each other, when member 70 is rotated, to adjust them to the position desired. The outer end of member 70 carries a crank and a handle 75 to facilitate the rotation thereof.

The clamping member 71 is to abut or clamp 45 against the forepart of the upper 3 on last 4 and comprises a pair of interengaging sections 76, 77 and a latching member 78 for coupling the sections together. The section 76 is bifurcated as at 79 and has one of the walls of the furcation transversely grooved, as at 80. The section 76 is of rectangular contour and provided near its 50 top with an opening 81 for the passage of member 70. The opening 81 extends from the front to the rear side edge of section 76 and has its wall threaded for engagement with the threads 73 of member 70. The section 77 includes a shank 82 carrying a head 83 of oval-shape contour in lengthwise section. The head 83 has its 55 bearing face covered by a strip 84 of cushioning material. The rear face of shank 82 has a transverse groove 85 adapted to register with groove 80 to form a circular opening for the passage 60 of the latching member 78, the latter being of greater length than the width of section 76, 77 and projects from the side edge of the latter. The member 78 comprises a bar 86 of circular 65 cross section having a part of one side cut-away to form a flat surface 87 aligning with the axis of the bar. One end of the latter is enlarged, as at 88 and carries a finger piece 89 to facilitate the shifting of member 78 when extended through the circular passage. The other end of bar 86 carries a retaining pin 90. When the circular 70 part of bar 86 is in grooves 80, 85 the sections 76, 77 are detachably connected together. By rotating bar 86 so that surface 87 will oppose either opening 80, 85, the section 77 can be removed from section 76.

The clamping or abutment member 72 comprises a pair of oppositely disposed like sections 91, 92 connected together by holdfast means 93, and each section has its inner face formed with a transverse groove 94 having the wall thereof threaded. Each section has its lower end serrated or knurled, as at 95. The grooves 94 register to provide a circular passage through which passes member 70. The threads on the walls of grooves 94 engage with the threads 74. The lower face of member 72 inclines upwardly from front to rear.

The lower ends of the latching members 44 are pivotally connected to the outer end of a locking lever 96, and the latter comprises a tapered body part 97 provided at its outer end with a pair of spaced collars 98 to which the lower ends of members 44 are pivotally connected, as at 99. The inner end of lever 96 is formed with a pair of spaced sleeves 100 for pivotally mounting on a bar, support or shaft 108. When lever 96 is swung outwardly with respect to support 108 the members 44 are carried therewith thereby lowering the hanger 37 and to position members 71, 72 against the work and last respectively. When members 44 are moved outwardly by the lever 96 to an extent whereby such members are off center, such as shown in Figure 1, due to the lower end of lever 96 being extended outwardly beyond support 108 the clamping element 2 is in active position to maintain the work in fixed position on element 1 during the operation of the latter to provide a sole leveling, shaping and securing position. The locking of the clamping element 2 in active position is had 100 against the action of the springs 62, the latter also assisting in elevating the front end of hanger 37 when element 2 is released from its locked set position. The shifting of element 1 105 to a position to hold the work is had manually by pulling down the outer end of hanger 37. The clamping element 2 can be released manually by shifting the outer end of lever 96 inwardly, and it can also be released automatically if the unit is mounted in a revolving carrier, and the 110 manner in which the automatic unlocking of element 2 can be had will be presently referred to.

After the clamping element 2 has been moved to a position to maintain the work on the pressing element 1, the handle 34 is shifted to open the continuous compressed air supply to chamber 16 for the purpose of building up a continuous pressure on member 12 to perform the sole leveling, shaping and securing operation. The shutting off of the compressed air to chamber 16 and opening the latter to the atmosphere can be had manually, or if the unit is mounted on a revolute carrier the shutting off of the air supply and the opening of the chamber 16 to the atmosphere can be had automatically, and the manner in which the automatic action can be had will be presently referred to. It is to be understood that the unlocking of the clamping element 2 and opening to the atmosphere of the presser element 1 can be had either manually or automatically, but that the unit does not depend upon the structure for carrying out the automatic action, as this invention relates solely to the unit, irrespective of what means is employed in connection with handle 34 for opening element 1 or for action upon lever 96 to release element 2.

With reference to Figures 1, 2, 4, 5 and 6, the sole leveling, shaping and securing unit is shown by way of example, on one form of a mounting for the unit, such form of mounting consists of 115

- parts of a revoluble carrier, such as shown in my application aforesaid and no claim is made herein to any of the features of the carrier, as the invention in this application relates solely to the unit.
- 5 The carrier includes a pair of bodily revoluble discs 102 for moving in unison. Stay rods, only one shown, and indicated at 67 connect the discs together. The stay rod 67 is the support upon which the uprights 63 are secured at their lower ends. A compressed air conducting pipe 103 is mounted in a pair of castings 104 secured to and extending outwardly from the outer edges of the discs 102. One end of pipe 103 is capped, as at 105 and its other end 106 leads to a compressed air supply. Mounted in the castings 104 are spaced rock shafts 107, 108 provided at one end with crank arms 109, 110 respectively carrying rollers 111, 112 respectively which coact with a cam mechanism, not shown for rocking shaft 107 20 in advance of shaft 108. The other ends of shafts 107, 108 carry oppositely extending crank arms 113, 114 respectively provided with pins 115, 116 respectively attached to controlling springs 117, 118 anchored to one of the discs 102. The shafts 107, 108 are rocked in one direction against the action of their controlling springs. One of the castings 104 has a stop 119 for arresting the return movement of crank arm 110.
- The stay rod 67 is arranged rearwardly and in spaced alignment with pipe 103. Removably connected to stay rod 67 and pipe 103, is a support 120 having the top of its front formed with an upwardly directed annular extension 121 and the bottom of its front with a depending annular extension 122. The shaft 107 is journaled in extension 121 and the shaft 108 in extension 122. The sleeves 100 of locking lever 96 are loosely mounted on shaft 108. Carried by shaft 107 is a collar 123 provided with a pin 124 adapted, when shaft 107 is rocked in one direction to actuate valve 30 to close the compressed air supply to element 1 and to open the latter to the atmosphere for exhaust. The shaft 108 has fixed thereto a pair of collars 125, each having one end provided 40 with a lateral lug 126. The lugs 126 are adapted, when shaft 108 is rocked in one direction, to engage lugs 127 on sleeves 100 for the purpose of moving the outer end of lever 96 inwardly to shifting members 44 to release clamping element 2. The rocking of shafts 107, 108 depends upon the travel. The cam mechanism, not shown, is positioned in the path of the rollers 111, 112. When shafts 107, 108 are rocked by the coaction of the rollers with the cam mechanism it provides for the automatic cutting off of the compressed air supply to element 1 and the unlocking of element 2.
- 50 What I claim is:—
1. A sole leveling, shaping and securing unit comprising a compressed air operated presser element, a valve movable to admit air under pressure to and to vent said element, means for clamping a shoe on said presser element, said last mentioned means including a releasable locking means shiftable to an off center position for maintaining said clamping means in clamping position, and separate means forming lost motion connections with said valve and with said releasable means respectively for moving said valve to venting position and for moving said releasable locking means to a position to release said clamping means.
- 10 2. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 15 3. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 20 4. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 25 5. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 30 6. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 35 7. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 40 8. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 45 9. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 50 10. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 55 11. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 60 12. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 65 13. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 70 14. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
- 75 15. A sole leveling, shaping and securing unit comprising a support, a compressed air operated presser element mounted on said support, a valve adjacent said support and movable to admit air under pressure to and to vent said element, means mounted on said support and extending above said presser element for clamping a shoe on said presser element, means normally urging said clamping means to unclamped position, a locking lever fulcrumed on said support, a link pivoted to said lever at a point spaced from said fulcrum, said link having an offset intermediate portion whereby its lower end may be swung downwardly past the fulcrum of said lever to lock said clamping means in clamping position, and separate means on said support movable to shift said valve to venting position and to shift said locking lever past its fulcrum to release said clamping means.
